UNITED STATES PATENT OFFICE

2,004,588

OPERATING DEVICE FOR CAR COUPLERS

Arthur E. Small, Chicago, Ill., assignor to Union Metal Products Company, Chicago, Ill., a corporation of Delaware

Application March 14, 1931, Serial No. 522,572

1 Claim. (Cl. 213—17)

This invention relates to a device for operating a railway car coupler mounted upon the car for lateral and longitudinal movement and having a pivoted knuckle provided with a tail engageable with a knuckle lock to which such an operating device is connected. The invention relates specifically to a railway car coupler having an anti-creep feature which is so formed that the lock can be raised to an unlocked position 5 by the operating device, but cannot be raised by the creeping action of the locks due to the service movements of the car. Some of such couplers are provided with a member mounted upon the coupler and arranged to operate the coupler upon 10 rotation of an operating rod operatively attached thereto.

Another object is to provide such a device which accommodates the longitudinal and lateral service movements of the coupler without affecting 15 the efficiency of the device.

Another object is to provide a device wherein the handle thereof will return to normal vertical position when the coupler is left in lock-set position.

Another object of the invention is to provide 25 such an operating device which is operable from anywhere between the coupler and the side wall of the car so that a trainman may throw the knuckle lock with one hand and operate the coupler with the other hand.

Another object of the invention is to provide 30 a car coupler operating device which may also be used as a car coupler positioning device; that is, may be used to position the coupler laterally.

Another object is to provide a device having an 35 operating rod which forms the handle of the device and is so arranged that a man's hand will not slip off the handle, which is possible in a device having a depending handle.

The Interstate Commerce Commission safety 40 appliance acts specify that the depending handle of an operating rod for car coupler shall not exceed fifteen inches (15") from the center of the fulcrum to the end of the handle, therefore, 45 the mechanical leverage obtainable by such a handle is the distance from the center of the operator's hand to the fulcrum, which is usually about twelve inches (12"). However, when an operator grabs the horizontal portion of my device 50 from the center of his hand to the fulcrum (bracket bearing) is the full fifteen inches (15") and the device complies with the law, therefore, the lever arm has been increased about twenty-five percent (25%).

55 In other words, with the same amount of force

applied my mechanism is twenty-five percent (25%) stronger than the device now in general use.

Another object of the invention is to provide a horizontal step for trainmen climbing up or down the car, which might also be used as a horizontal grab iron for a trainman caught between the cars.

Another object of the invention is to provide an operating rod for such a coupler having a 10 stabilizer which is associated with a part of the car (preferably a bracket mounted on the car) so as to stabilize the rod by gravity against a rotative movement thereof which would release the coupler anti-creep feature. The device is 15 preferably arranged to stabilize the rod against a rotative movement in either direction, as a swinging movement of the handle toward the car might cause a swinging movement away from the car, which latter movement would unlock the 20 anti-creep.

In the drawing:

Figs. 1, 2 and 3 show the preferred form of the invention.

Figs. 4, 5 and 6 show a modified form wherein 25 the upright portion of the operating rod is provided with a substantially horizontal portion forming a handle.

Figs. 7, 8 and 9 show a modified form of the device provided with a stabilizer.

The coupler 2, as is customary, is mounted upon 30 the car so as to move laterally and longitudinally thereof in service. The coupler comprises a member 3 arranged to operate the coupler which member is usually supported below the coupler 35 head 4 by means integral with the coupler. (A typical coupler of this type is shown in Kinne Patent No. 1,639,300, August 16, 1927.)

Figs. 1, 2 and 3 show the preferred form of my 40 invention comprising a bracket mounted upon the car and an operating rod. The operating rod comprises a substantially horizontal shank 5 with its inner end operatively connected to the member 3 of the coupler and a substantially upright member 4 hinged to the outer end of the shank 5 45 to move relative to each other only in their common plane which member is supported at its upper end upon the bracket 7 so that as the coupler moves laterally in service the member swings back and forth upon the bracket. The rings 8—8 50 form a handle to keep the operator's fingers away from the hinge joint.

In order to stabilize the device and prevent it 55 from swinging, which might rotate the rotor of the coupler or unlock the coupler anti-creep lock,

I prefer to provide a point of contact 10 between the upright member 4 of the operating rod and an element 12 on the car, as shown in Fig. 3. Furthermore, I prefer to position the outer end 5 of the operating rod beyond a vertical plane 14 passing through the fulcrum point 15 of the bracket 7 so the weight of the rod has a tendency to swing the upright member toward the car, as shown in Fig. 3.

- 10 The device is operated by swinging the operating rod around the bracket 7, which is done by preferably catching hold of the rod 5 adjacent the upright member 4. However, the rod may be grabbed anywhere between its connection to the coupler and the upright member 4. Furthermore, the coupler can be moved laterally by means of this operating rod forming what is commonly called a positioning device.

Figs. 4, 5 and 6 show the hinge connection 20 between the shank 21 and upright member 22 of the operating rod positioned far enough away from upright member to form a handle 23 for the operator without catching his fingers in the hinge parts.

- 25 Figs. 7, 8 and 9 show a modified construction wherein the device is provided with a stabilizer for the operating rod which, in the form illustrated, comprises a relatively wide bar 30 providing a bearing on the bracket and the upright member 31 of the operating rod is formed with spaced apart portions 33-34 engaging the margins of the bar so that as the operating rod is swung the weight of the operating rod is shifted to one of said portions, causing a tendency for 30 the rod to return to normal position by gravity. The top of the loop forming the spaced apart por-

tions is arched to clear any accumulation of dirt or ice on the bar. An aperture may be provided to allow dirt and snow to fall through.

In my application Serial No. 522,573, filed March 14, 1931, which matured into Patent No. 1,915,387, on June 27, 1933, upon improvements in "Car coupler operating device" I have disclosed and claimed certain features disclosed but not claimed in this application.

The accompanying drawing illustrates the preferred form of the invention, though it is to be understood that the invention is not limited to the exact details of construction shown and described, as it is obvious that various modifications thereof, within the scope of the claim, will occur to persons skilled in the art.

I claim:

In a railway car, an operating device for use with a car coupler mounted upon the car to move laterally in service and having a member mounted upon the coupler arranged to operate the coupler upon rotation of an operating rod, said device comprising a bracket mounted upon the car, an operating rod having a shank operatively connected to the member at its inner end, and a substantially upright member loosely supported at its upper end by said bracket to swing lengthwise and sidewise of the car, the lower end of said upright member having a horizontal portion extending inwardly toward the coupler substantially 30 in alignment with said shank and forming a handle hingedly attached at its inner end to the shank in such manner that said upright member and shank move relative to each other only in a single plane.
